[57] **ABSTRACT**

A fluid pressure operated switch comprises an electrically conductive body having a passage therethrough, a diaphragm engaging a shoulder on the body around the passage and lying across the latter, and a contact plate spring biased into engagement with the diaphragm. The diaphragm is formed of a flexible, compressible material which becomes electrically conductive when compressed. The pressure applied by the spring acts on a portion of the diaphragm lying against the shoulder and is normally sufficient to render that portion electrically conductive so that the contact plate is normally electrically connected with the body. When a sufficient pressure exists in the passage, the pressure applied by the spring on the said portion of the diaphragm is reduced to an extent such that the diaphragm is no longer electrically conductive and the contact plate is electrically isolated from the body.

**PRESSURE SWITCH WITH DIAPHRAGM FORMED
OF FLEXIBLE COMPRESSIBLE MATERIAL
CONTAINING DISCRETE ELECTRICALLY
CONDUCTIVE PARTICLES WHICH MAKE AND
BREAK THE CIRCUIT**

This invention relates to a fluid pressure operated switch.

A fluid pressure operated switch in accordance with the invention comprises a body having a passage therethrough and at least a contact portion which is of conductive material, a diaphragm extending across said passage and formed of a flexible compressible material containing discrete particles of electrically conductive material which are brought into contact with one another to establish conductive paths through the material when the material is compressed, a contact member spring biased into engagement with said diaphragm so as to compress a portion of said diaphragm between the contact member and the contact portion of the body, the arrangement being such that the application of sufficient fluid pressure to said passage to overcome spring bias on the contact member deforms the diaphragm so that the portion thereof which is compressed between the contact member and the contact portion of the body is disengaged from the contact member so as to break the electrical connection between the contact member and the contact portion of the body.

An example of the invention is shown in the accompanying drawing which is a longitudinal cross-section through a switch according to the present invention.

The switch shown includes a body 10 formed of an electrically conductive material, such as aluminium. The body 10 has a passage 11 therethrough which terminates at a shoulder 12 defining a contact portion. Mounted on the body is an insulating cap-shaped member 13 which carries a terminal 14 connected to a conductive contact disc 15 through the intermediary of a spring 16 which urges the contact member 15 towards the open end of the passage 11.

Overlying the shoulder 12 on the body 10 is a diaphragm 17 formed of a known material consisting of discrete particles of a conductive material in a compressible matrix such that compression of the matrix between contact portion of the body and the contact member 15 will cause an electrical path to be established between said contacts only through the compressed portion of the matrix. The contact member 15 is of larger diameter than the passage 11 so that it overlies a portion of the shoulder 12 forming the contact portion of the body. The spring 16 urges the contact member into engagement with the diaphragm 17 and compresses a portion of it overlying the contact portion of the body. Thus, when there is no pressure applied in the passage 11, a conductive path is established between the terminal 14 and the body 10.

The cup-shaped member 13 has a counter-bore at its

end which slidably receives the contact member 15. The outer end of this counter-bore has a flared mouth 18 so that the diaphragm 17 is free outwardly of the contact member 15 to be displaced towards the terminal 14. Thus, when a sufficient fluid pressure is applied to the passage 11 to overcome the biasing of the spring 16 the diaphragm 17 is deformed to a shallow cup shaped configuration with the contact member 15 engaging the centre portion of the diaphragm 17 but not the portion thereof overlying the shoulder 12.

It will be appreciated that when there is no pressure applied to the passage 11 the entire force applied to the contact member 15 by the spring 16 is absorbed through a narrow annular portion of the diaphragm 12 overlying the contact portion on the body. When the diaphragm is deformed, however, the force of the spring 16 is taken by the centre portion of the diaphragm, and insufficient pressure is applied to the diaphragm over the contact portion on the body to compress the diaphragm sufficiently to cause conductive paths to be established through it.

I claim:

1. A fluid pressure operated switch comprising a body having a passage therein and at least a contact portion which is of conductive material, a diaphragm extending across said passage and formed of a flexible compressible material containing discrete particles of electrically conductive material which are brought into contact with one another to establish conductive paths through the material when the material is compressed, a contact member spring-biased into engagement with said diaphragm so as to compress a portion of said diaphragm between the contact member and the contact portion of the body, the arrangement being such that the application of sufficient fluid pressure to said passage to overcome spring bias on the contact member deforms the diaphragm so that the portion thereof which is compressed between the contact member and the contact portion of the body is disengaged from the contact member so as to break the electrical connection between the contact member and the contact portion of the body.

2. A switch as claimed in claim 1, wherein the contact portion of the body is provided by a shoulder therein against which the diaphragm abuts.

3. A switch as claimed in claim 2, wherein the diaphragm is lodged between the shoulder and an electrically insulating hollow member in which is disposed the contact member.

5. A switch as claimed in claim 3, wherein the hollow member carries a terminal electrically connected with the contact member via the spring which is lodged in the hollow member.

5. A switch as claimed in claim 3, wherein a portion of the hollow member surrounding the contact member is defined by a flared mouth which engages the diaphragm.
